UNITED STATES PATENT OFFICE.

RENE C. CURTIS, OF MARTINEZ, CALIFORNIA.

DISPENSING CABINET.

Application filed January 20, 1926. Serial No. 82,548.

This invention relates to vending cases or cabinets.

An object of my invention is the provision of a vending cabinet in which the packages 5 are dispensed in the order in which they are put in so that comparatively old supply is sold before the latest supply.

Another object of my invention is the provision of a vending cabinet in which the 10 displays are placed in front of, and separate from, the corresponding stacks and both embodied in or constructed on the door of the cabinet.

The cabinet hereinafter described, having 15 been invented primarily as a dispensing cabinet for cigarettes, it may be mentioned that cigarette packages are frequently stacked in pigeonholes by the retailer, the front package in each pigeonhole indicating 20 the brand of cigarettes therein.

For the sake of appearance the dealer desires to keep every pigeonhole fully stacked. This requires him, every time he sells a package, to go to his larger stock for a package 25 of the kind just sold and put it in the place of the latter. Not only does this method of retailing entail much waste of labor but, as will be readily seen, the second or third package from the front will at times be sold after 30 they are too old to be acceptable to the customer. Such may happen when a customer buys two or more packages at a time of the same brand of cigarettes, or when two or more packages are sold in quick succession 35 from the same pigeonhole.

In the cabinet of my invention, however, the packages that are first placed in the dispensing compartments are the first to be sold; furthermore the stack in the cabinet 40 need not be replenished whenever a single package of cigarettes is sold, since all except one or two of the packages of each brand are out of sight of the customer.

Other objects and advantages will be 45 readily appreciated by those skilled in the art.

In the drawings which illustrate my invention—

Figure 1 is a front elevation of a dispensing cabinet and fragmentary similar cabinets above and below the cabinet shown in full.

Figure 2 is a plan view of the cabinet shown in Figure 1.

Figure 3 is a section taken on the line 3—3 of Figure 1.

Figure 4 is a section on the line 4—4 of Figure 1.

Figure 5 is a plan view similar to that shown in Figure 2 except that the door of the cabinet in this view is open, whereas in 60 Figure 2 the door is shown closed.

Referring to the drawings for more detailed description thereof, the dispensing cabinet comprises a bottom 7, a back 8, a top 9, sides 10 and 11 and a door 12, hinged to 65 the side 10, having at positions 13 a knob 14. It will be noticed that the door 12 does not entirely close the cabinet, but extends downwardly to the position 15, the purpose of which construction will hereinafter be apparent.

The upper portion of the door is hollow, and in this hollow space are disposed spaced parallel, vertical partitions 17, which with the rear wall 18 of the door and a pane of 75 glass 19 in front of the back 18, form compartments 20 shown in Figures 1 and 3 as being slightly greater in width than the width of two superimposed packages of cigarettes 21. Different brands of cigarettes 80 may be placed in each compartment 20 for display purposes only. The packages may be readily placed in the compartments 20 as the latter extend to the top of the door and are open.

Chutes are constructed on the back of the door there being a chute directly in back of the compartments 20. These chutes are numbered 23 and are formed by vertical partitions 24 which are in alignment with the 90 partitions 17, which form compartments 20, adapted to receive display packages. The chutes 23 are adapted to receive stacks of cigarette packages which are to be vended. It will be noted that the partitions 24 extend below the door 12. Transversely to the rear edges of the partitions 24 are disposed members 25 which each extend to either side of their respective partitions, thus forming means for retaining the cigarette packages 95 in their chutes.

Transversely to and at the bottoms of the partitions 24, are secured members 27 which each extend to either side of their respective partitions 24. The members 27 it will be 105 readily seen, prevent the stacks of cigarettes

from falling out of their respective chutes. It will be noted that the members 25 do not extend as far back as the rear wall 8 of the cabinet, and it will also be noticed that the 5 stack-retaining members 27 are above the bottom 7 of the cabinet. The space between the bottom 7 of the cabinet and the members 27 is sufficient to allow of the hand being placed therein, so that the fingers of a hand 10 may be extended to the rear of the vertical members 25 and there be employed to push forwardly from a chute the bottom package of cigarettes. When the bottom package of a stack has been withdrawn, the remaining 15 packages readily fall downwardly until the then last package comes into contact with the members 27.

It will be readily appreciated that if desired another row of chutes may be built 20 and disposed back of the chutes 23 herein shown and described, and may extend to a point below the latter chutes.

It will be readily seen from the foregoing description and the drawings accompanying 25 the same that when the two lowermost packages of a stack are exposed to the view of the customer, which feature allows packages to be withdrawn from a stack until only two are left; while as far as the customer is concerned, the chute seems to be full. It will 30 also be apparent that according to the arrangement described and illustrated the display packages are separate from the packages to be vended so that the former are not 35 disturbed by the vending of the latter as is the case in some systems of retailing now employed.

Although I have shown and described one 40 embodiment of my invention, it is to be understood that the same is susceptible of vari-

ous changes; and I reserve the right to employ such as may come within the scope of the appended claims.

I claim:—

1. In an article of the character described, 45 a casing, a door closing the upper portion of said casing, a row of straight vertical chutes on the back of said door and extending below the door but terminating above the bottom of said casing, strips at the lower ends of said chutes for holding packages in said chutes, said casing being open in the lower part thereof so that a hand may reach into said casing under said door, there being a space between the back of the chutes and the 50 back of the casing large enough for a hand to engage the back of the lowest package in a chute and slidably pull it therefrom.

2. In an article of the character described, 55 a casing, a door closing the upper portion of said casing, a row of straight vertical chutes on the back of said door and extending below the door but terminating above the bottom of said casing, strips at the lower ends of said chutes for holding packages in said chutes, said casing being open in the lower part thereof so that a hand may reach into said casing under said door, there being a space between the back of the chutes and the 60 back of the casing large enough for a hand to engage the back of the lowest package in a chute and slidably pull it therefrom, said door being provided at its front with closed compartments, one for each said chute, and adapted to be filled with dummy packages of 65 the goods displayed in its corresponding chute, each said compartment having a transparent front.

RENE C. CURTIS.
